UNITED STATES PATENT OFFICE.

ANDREW M. SIMS, OF SAN FRANCISCO, CALIFORNIA.

RAZOR-STROP HOLDER.

1,187,191.

Specification of Letters Patent. Patented June 13, 1916.

Application filed July 31, 1914. Serial No. 854,286.

To all whom it may concern:

Be it known that ANDREW M. SIMS, a citizen of the United States, and a resident of San Francisco, county of San Francisco, and State of California, (whose post-office address is San Francisco,) prays that Letters Patent may be granted to him for Improvements in Razor-Strop Holders set forth in the annexed specification.

10 This invention relates to improvements in razor strop holders and has particular application to a yieldable strop holder.

In carrying out the present invention, it is my purpose to provide a razor strop holder of the class described whereby the strop will be permitted to give or yield under the pressure of the razor blade in the stropping operation so that the razor blade may be stropped evenly and uniformly.

20 It is also my purpose to provide a razor strop holder which will embrace the desired features of simplicity, efficiency and durability, which will operate efficiently and effectively for its intended purpose and which 25 may be manufactured and marketed at a minimum expense.

With the above and other objects in view, the invention consists in the construction, combination and arrangement of parts hereinafter set forth in and falling within the 30 scope of the claim.

In the accompanying drawing, Figure 1 is a perspective view of a razor strop holder constructed in accordance with the present 35 invention. Fig. 2 is a sectional view through the holder. Fig. 3 is a sectional view taken at right angles to Fig. 2. Fig. 4 is a plan view of the blank from which the support is made.

40 Referring now to the drawing in detail, 1 designates a support formed of a single sheet of metal 2 bent upon itself approximately centrally of its ends as at 3 to form an end wall 4 and side walls 5, 5 projecting 45 outwardly from the end wall 4 at right angles to the latter and spaced apart in parallelism. Formed integral with the outer ends of the side walls 5, 5 are clamping plates 6, 6 respectively offset inwardly from 50 the respective side walls and designed to receive and frictionally engage one end of a razor strop S. In the present instance, the clamping plates 6, 6 are formed with alining openings registering with an aperture in the strop S and through these registering openings and aperture is passed a 55

clamping bolt 7 having a head on one end and the remaining end portion threaded to receive a clamping nut 8 whereby the inner surfaces of the clamping plates 6 may be 60 brought into binding engagement with the end portion of the razor strop between such plates.

Formed in the end wall 4 approximately centrally thereof is an opening 9 and 65 through the opening 9 is passed a shank 10 having the outer end thereof formed with an eye 11 designed to receive a hook, nail or other support. In the present instance, a nut 12 is threaded onto the inner end of the 70 shank 10 and encircling the shank 10 between the nut 12 and the inner surface of the end wall 4 is a coiled expansion spring 13 having the opposite ends thereof disposed within and bearing against cups 14, 14 75 disposed, respectively, adjacent to the nut 12 and end wall 4 and forming bearings for the ends of the spring 13. In the present instance, the material from which the support is formed is stamped to provide wings 15, 80 15 formed integral with the end edges of the wall 4 at right angles to the walls 5 and these wings are bent at right angles to the end wall 4 and coöperate with the walls 5 to inclose the shank 10, spring 13 and cups 85 14, the side walls 5 and 15 forming a dust-proof housing for the spring and associated parts.

In the use of the device, the eye 11 is 90 passed over a hook, nail or other support and the free end of the strop S grasped with one hand of the user. The razor blade is now moved back and forth over the strop S in the usual manner and as the blade is forced against the strop under pressure in 95 the stropping operation the support composed of the side walls 5, end wall 4, clamping plate 6 and walls 15 moves along the shank 10 against the action of the spring 13 so that the pressure of the blade on the 100 strop will remain uniform irrespective of the pressure on the blade, thereby insuring the even and uniform stropping of the blade.

I claim:

A razor strop holder comprising a support formed of a single sheet of metal bent upon itself centrally to form an end wall and side walls depending from said end wall parallel with each other, clamping 110 plates formed on the lower ends of said side walls and offset inwardly from the

105

110

respective side walls to receive one end of the strop, wings formed integral with the edges of said end wall at right angles to said side wall and depending from said end wall and coöperating with said side walls to form a closed casing, and resilient means within the casing so formed for supporting the strop holder.

Signed at San Francisco, in the county of San Francisco, and State of California, 10 this 13th day of July, 1914.

ANDREW M. SIMS.
